COLLAPSIBLE TUBE DISPENSER

Harland J. Fogarty and Eva A. Fogarty,
San Bernardino, Calif.

Application June 17, 1949, Serial No. 99,762

1 Claim. (Cl. 222—103)

1

This invention has to do with improvements in devices for dispensing the contents of collapsible tubes.

We are aware that various devices have been proposed for ejecting paste and the like from collapsible tubes, but such prior devices have possessed shortcomings which it is an object of the present invention to overcome.

It is a further object to provide simple and efficient means for evenly collapsing a collapsible tube in such a manner as to eject only the desired amount of the contained material during each operation, and yet so as eventually to eject substantially all the material from the tube by effecting complete collapse.

A further object is to provide an economical, one-piece tube collapsing clamp which is capable of collapsing the walls of the tube completely and evenly against each other.

Another object is to provide a clamp of this character which is so constructed that it will remain in engagement with the tube without the aid of auxiliary retaining means.

Such prior devices as did come to our attention have been of such inherent construction that they are incapable of fully stripping a tube and incapable of ejecting all the contents therefrom—that is, they have been capable of ejecting only a portion of the contents. It is therefore a further object of our invention to provide in a single device a combination of elements which enables a stripping and ejecting result far superior to anything which has heretofore been proposed.

Another object is to provide a dispenser of this type incorporating an efficient and convenient hanger for the tube being collapsed.

Another object is to provide a device of this character which may be operated readily and efficiently with or without a hanger for the tube, and, in either case, with but one hand, leaving the other hand free to hold a brush or the like to receive the contents of a tube as ejected.

Further objects will appear hereinafter.

Without any intention of thereby limiting the scope of the invention, but rather for the purpose of explaining how it may be carried into practice, we shall now describe the invention in one of its presently preferred embodiments, for which purpose we shall refer to the accompanying drawings, wherein:

Fig. 1 is a side elevation showing the parts in position on a tube;

Fig. 2 is an elevation taken on the line 2—2 of Fig. 1;

2

Fig. 3 is a side elevation showing the tube substantially collapsed and detached from the hanger;

Fig. 4 is a side elevation of the tube clamping member;

Fig. 5 is a top plan view taken on the line 5—5 of Fig. 4;

Fig. 6 is an elevation taken from the right of Fig. 4;

Fig. 7 is an enlarged section taken on line 7—7 of Fig. 6;

Fig. 8 is an elevation showing a tube substantially flattened and the clamping member reversed end for end for the purpose of finally stripping the tube; and

Fig. 9 is an enlarged view, partly in elevation and partly in section, showing the manner of applying the suspending link to a tube.

In general, we carry the invention into practice by combining in a single, simple one-piece device means for initially substantially collapsing a tube, means for giving the main body of the tube a secondary and more thorough stripping operation, and means for finally ejecting that

portion of the contents of a tube which tend to collect beneath the relatively rigid concave end wall of the discharge end of the tube. The device includes generally a pair of clamping jaws connected at one end by a pair of spaced arched resilient webs, which permit the jaws to be moved into efficient stripping engagement with a tube since they are capable of being moved into full and complete face to face contact with each other, such contact first occurring at the converging extremities of the jaws and increasing sufficiently in intensity at that point during further closure to prevent backflow of contents as well as back movement of the device on the tube.

At the opposite ends of the jaws, we provide special protuberances for engaging beneath the concave end wall of a tube, to eject material tending to collect at that point, and the device incorporates provision for so locking the jaws of the clamp in clamping engagement with the flattened portion of the tube as to prevent backflow of the material from said end portion as the final stripping operation is performed. By this arrangement, we provide extreme simplicity of construction and efficiency of operation. In the preferred form of the invention, we also provide an efficient hanger for the tube, the clamp and hanger having contiguous end portions so formed as to permit the clamp to commence its ejecting operation at the extreme end of the tube.

In the following description we describe our

device as applied to the collapsing of a conventional toothpaste tube, although it will be understood that it is capable of use for collapsing tubes of various sorts.

Referring to the drawings, the numeral 5 generally denotes the clamp element, the letter T denotes a collapsible tube such as a conventional toothpaste tube, and the numeral 6 denotes a hanger.

The clamp 5 is preferably a stamping made, for instance, from a sheet of ST dural, although other materials will suffice, the only requisite being that the material should be somewhat resilient.

The clamp comprises a pair of flat jaws 15 connected by two arched side portions or webs 17 defined by cutting away portions of the material between the portions 17. To facilitate even collapsing of the tube as well as to facilitate operation, it is our preference to curve the lower ends 18 of the jaws outwardly and upwardly.

So as to enable full collapsing of the tube, the arched portions 17 curve inwardly to intersect the top ends of the jaws as shown at 20, thus pre-stressing the clamp in such a manner that the upper ends of the jaws are normally separated only by a very narrow space 36, which is a distance less than the thickness of the sealed upper end E of the tube, but slightly greater than the thickness of the flattened tube, so that when the tube is sandwiched between the jaws it is movably retained between the upper ends of the jaws. The inner edge surfaces of the portion 17 are preferably smooth so as to permit free movement relative to the tube.

The upper end of each jaw between the web 17 terminates in a flange 38 which intersects the contiguous end portion of the jaw in a curve of very small radius. This construction not only imparts transverse rigidity, but also provides appropriately rounded tube engaging surfaces.

The hanger 6 comprises a U-shaped bracket 25 whose medial wall has screw or rivet holes to receive attaching rivets or screws 26 by which it may be attached to a shelf or the like. A cross pin 28 is secured at its ends to the end legs of the bracket and a substantially U-shaped resilient tube suspending link 30 is suspended from the cross pin. The free ends 31 of the link are inturned so as to engage beneath the sealing strip S customarily provided to seal the end of a toothpaste tube.

The link 30 is narrow enough to enter between the arched portion 17 of the clamp and thus to permit the link to engage the end of the tube when the clamp is first mounted thereon and before the collapsing of the tube is commenced.

Insertion of the end of the tube between the side walls of the link 30 is rendered easy by simply first sliding the link upwardly on the cross pin 28, as shown in Fig. 9, which spreads the free ends of the link apart far enough to permit insertion of the end of the tube. The link is then moved back on the cross pin, which permits the free ends of the link to clamp the end of the tube therebetween, as shown in Figs. 1 and 2. Before thus attaching the tube to the link, the upper end of the tube is inserted between the jaws 15 of the clamp.

Thus, by removing the screw cap C from the discharge neck of the tube and manually urging the jaws of the clamp together, the tube is evenly collapsed without forming wrinkles in the tube, and the desired amount of paste is ejected from the tube onto a toothbrush which may be held below the discharge neck of the tube. Such op-

erations are repeated with the clamp moving downwardly along the flattened portion of the tube after each operation, until the tube is in the condition of Fig. 3 in which position the tube is flattened except for that portion immediately behind the concaved end wall W of the tube. Complete stripping of the remaining contents from the thus flattened portion of the tube may then be accomplished by raising the clamp on the tube to the sealing strip several times and, while pressing the jaws firmly together at the point where they converge, drawing the clamp down the flattened tube as far as the jaws will permit. By inverting the clamp on the tube, stripping of the remainder of the flattened portion of the tube may be accomplished in the same manner and the clamp is then in position to proceed with the final operation of ejecting the paste from the unflattened portion immediately behind the concave end wall W of the tube. Said end wall is usually relatively stiff as compared with the body of the tube and thus resists collapsing at that point. To eject the paste within that portion of the tube we therefore provide an additional feature on the clamp which will now be described.

The upper end of each of the clamp jaws, between the arched portion 17, has a protuberance 35 formed on each side of the space 36 between the upper ends of the jaws. Each of these protuberances is formed by providing an integral extension portion 39 on the outer edge of the flanged portion 38 and then curving the extension portion upwardly and inwardly. These protuberances 35, together, are preferably ovate in plan and each is convexly curved in cross-section and in elevation so that with the flattened tube between them they will fully fill the span beneath the concave end wall of the tube. Preferably the protuberances are made large enough to fit under the end wall of the largest tube that the width of the clamp will accommodate so that they will, by virtue of their shape, also fit under the end wall of a smaller tube. Inasmuch as each of these protuberances is shorter than the length of the flange of which it forms an extension, the two protuberances thus provided are in position medially between the webs to collapse the side wall of the tube under the concave end wall W of the tube, thus enabling a complete stripping job. To accomplish this final stripping operation, it is necessary to secure the jaws of the clamp fully closed on the tube as close to the end wall W as they will readily go, as shown in Fig. 8, in order to exclude the remaining contents from the previously stripped portion of the tube. In practice we find it preferable to secure the jaws in the fully closed position by bending the flattened upper end portion of the tube laterally over and under the curved end of first one jaw and then the other, as shown in Fig. 8. By then placing the thumb on the laterally bent tube securing the jaws and the first two fingers beneath the end wall of the tube and compressing the tube axially the protuberances are forced under the concaved end wall of the tube, expelling the contents therefrom.

Of course, our clamp dispenser may be utilized separately from the hanger—that is, the tube may be detached from the hanger, with the clamp 5 remaining thereon as shown in Fig. 3. Then, by holding the discharge end upwardly, the tube automatically moves downwardly within the clamp.

From the foregoing it will be apparent that

our device is extremely economical to manufacture, simple to use, and it accomplishes a cleaner, more even and more completely collapsed tube than has heretofore been possible with dispensers of the prior art.

We claim:

A one-piece tube collapsing dispenser comprising a stamping of resilient material shaped to provide a pair of opposed jaws adapted to receive a collapsible tube therebetween and connected together at their top ends by a pair of flexible, integral webs shaped to permit the jaws to swing into contact with each other and to swing apart; said webs being spaced apart far enough to permit said tube to pass therebetween; and each of the jaws having at its top end an outwardly, upwardly and inwardly disposed flange medially be-

tween and of a length less than the distance between the webs whereby when said dispenser is reversed end for end on said tube said flange fully collapses the outer end portions of the side walls of the tube against the outlet end wall thereof.
